US0D1047969S

(12) **United States Design Patent** (10) Patent No.: **US D1,047,969 S**
(45) Date of Patent: ** Oct. 22, 2024

(54) **MAGNETICALLY MOUNTED LOUDSPEAKER**

(71) Applicant: **Scosche Industries, Inc.**, Oxnard, CA (US)

(72) Inventor: **Yasuhiro Yamamoto**, Thousand Oaks, CA (US)

(73) Assignee: **Scosche Industries, Inc.**, Oxnard, CA (US)

(**) Term: **15 Years**

(21) Appl. No.: **29/791,129**

(22) Filed: **Dec. 30, 2021**

(51) LOC (14) Cl. **14-01**

(52) U.S. Cl.

USPC **D14/216**

(57) **CLAIM**

The ornamental design for a magnetically mounted loudspeaker as shown and described.

DESCRIPTION

FIG. 1 is a front perspective view showing a magnetically mounted loudspeaker;

FIG. 2 is a rear perspective view thereof;

FIG. 3 is a top plan view thereof;

FIG. 4 is a front view thereof;

FIG. 5 is a right side view thereof;

FIG. 6 is a left side view thereof;

FIG. 7 is a rear view thereof; and,

FIG. 8 is a bottom plan view thereof.

In the drawings, the broken line showings are for the purpose of illustrating environmental structure or portions of the magnetically mounted loudspeaker that form no part of the claimed design.

1 Claim, 4 Drawing Sheets
